DOUBLE-BALANCE CENTRIFUGAL PUMP.

1,395,464.

Specification of Letters Patent.

Patented Nov. 1, 1921.

Application filed August 3, 1920. Serial No. 401,010.

To all whom it may concern:

Be it known that we, WALTER R. WOOCK, HERBERT J. WOOCK, and ERIC M. WOOCK, citizens of the United States, residing at 5 Lodi, county of San Joaquin, State of California, have invented certain new and useful Improvements in Double-Balance Centrifugal Pumps; and we do declare the following to be a full, clear, and exact description of the same, reference being had to the accompanying drawings, to the characters of reference marked thereon, which form a part of this application.

This invention relates to improvements in 15 centrifugal pumps, being of the general design and principle shown in our co-pending application for patent filed July 31st., 1920, Serial No. 393,814, but incorporating therein in certain features of improvement.

20 The principal object of the present invention is to so arrange and construct the various parts of the pump, particularly of the casing, that a perfect double balance will be had, both on the vacuum and pressure 25 sides—that is, in the intake and discharge chambers—of the pump.

A second object is to construct the discharge or pressure chamber so that it completely surrounds the vacuum or intake 30 chamber, thus positively insuring against air leaking into the vacuum chamber, regardless of flaws or even holes in the latter, which would ordinarily suck air and materially reduce the efficiency of the pump.

35 A third object is to position deflectors in the discharge chamber in alinement with the runners whereby the water therefrom will be diverted into the central portion of the chamber, thereby preventing any churning 40 of the water.

The discharge chamber is also arranged as a whole relative to the runners, that the water will be taken from the spiral surrounding the runners at all points in the 45 periphery of the same, thus relieving the pressure on the runners, and tending further to reduce the possibility of churning.

50 A further object of the invention is to produce a simple and inexpensive device and yet one which will be exceedingly effective for the purposes which it is designed. These objects we accomplish by means of such structure and relative arrangement of parts

as will fully appear by a perusal of the following specification and claims.

55 In the drawings similar characters of reference indicate corresponding parts in the several views.

Figure 1 is a top plan view of the pump, half in section.

60 Fig. 2 is a cross section of the pump, taken substantially on the vertical center line thereof.

Referring now more particularly to the characters of reference on the drawings, the 65 numeral 1 denotes a central cylindrical casing 1 having an intake 2 in one side thereof and central of its length, this member forming the intake or vacuum chamber.

A vertical partition 3 practically divides 70 this chamber into two equal parts, the arrangement and purpose of this partition being as set forth in the aforementioned co-pending application.

This chamber also has end walls 4 provided with central orifices in which fit the inner and open ends of opposed runners 5, mounted on a shaft 6 which is concentric with the chamber 1.

75 These runners comprise spaced walls 7 having curved vanes 8 connecting the same, this construction and the arrangement thereof in connection with the chamber walls 4 being also as shown in our co-pending application No. 393,814.

80 Concentric with the casing 1, and formed therewith, and extending therebeyond over the plane of the runners is a cylindrical casing 9, forming the runner spirals 10 and a central chamber 11. End caps or covers 12 85 form the end walls of this casing, and are provided with bearings 13 for the shaft 6.

85 It will thus be seen that there is absolutely no possibility of air leaking into the intake chamber, since any such air would have to 90 pass through the chambers 10 and 11, and as a result water would be drawn into the intake chamber rather than air, which of course would not reduce the vacuum nor impair the efficiency of the pump. In the 95 spiral portions of the discharge or pressure chamber are radial and evenly spaced baffle-vanes or deflectors 14, these being so angled in a vertical plane that the water thrown by the runners 5 is immediately caught thereby 100 and diverted into the central chamber 11,

thus preventing any churning of the water in the spirals.

The chamber is provided with a centrally positioned discharge orifice 15, the adjacent 5 and corresponding deflectors in the runner spirals being connected together by a curved and longitudinal partition 16 which connects the casing 1 with the casing 9 and terminates along the latter casing at the edge 10 of the orifice 15 opposite to the direction of flow of the water, so that the water in the central chamber is positively diverted into the said orifice and cannot churn around in said chamber.

15 From the foregoing description it will be readily seen that we have produced such a device as substantially fulfills the objects of the invention as set forth herein.

While this specification sets forth in detail the present and preferred construction 20 of the device, still in practice such deviations from such detail may be resorted to and do not form a departure from the spirit of the invention, as defined by the appended 25 claims.

Having thus described our invention, what we claim as new and useful and desire to secure by Letters Patent is:

1. A centrifugal pump including a pair 30 of opposed runners, a common intake chamber therebetween, another chamber surrounding the intake chamber and extending over the runners, and deflectors arranged in the outer chamber adjacent the periphery of

the runners and adapted to direct the water 35 therefrom into the central portion of the outer chamber.

2. A centrifugal pump including a pair 40 of opposed runners, a common intake chamber therebetween, another chamber surrounding the intake chamber and extending over the runners to form the runner-spirals, deflectors in said spirals arranged to divert the water into the central portion of the outer chamber, said chamber being provided with a discharge orifice, and means whereby the water diverted into the said chamber will be positively discharged through said orifice.

3. A centrifugal pump including a pair 50 of opposed runners, a common intake chamber therebetween, another chamber surrounding the intake chamber and extending over the runners to form the runner-spirals, deflectors in said spirals arranged to divert 55 the water into the central portion of the outer chamber, said chamber being provided with a discharge orifice, and a longitudinal partition wall connecting the walls of said chamber and positioned adjacent one 60 edge of the discharge orifice, said partition wall being formed as an extension of a pair of corresponding deflectors.

In testimony whereof we affix our signatures.

WALTER R. WOOCK.
HERBERT J. WOOCK.
ERIC M. WOOCK.
